(57) **CLAIM**

The ornamental design for a ladder for a van, to be used with a van as shown and described.

DESCRIPTION

FIG. 1 is a left side elevation of a ladder for a van showing my new design;

FIG. 2 is a front view thereof;

FIG. 3 is a back view thereof;

FIG. 4 is a right side elevation view thereof;

FIG. 5 is an isometric view thereof; and,

FIG. 6 is an isometric view of ladder connected to van thereof.

The broken lines are for illustrative purposes only and form no part of the claimed design.
